UNITED STATES PATENT OFFICE.

MARY DEUELL GEORGE, OF WASHINGTON, DISTRICT OF COLUMBIA.

GAME.

1,294,256.

Specification of Letters Patent. Patented Feb. 11, 1919.

Application filed July 29, 1918. Serial No. 247,260.

To all whom it may concern:

Be it known that I, MARY DEUELL GEORGE, a citizen of the United States, residing at Washington, in the District of Columbia, have invented certain new and useful Improvements in Games, of which the following is a specification.

My invention relates to an improvement in games, and it consists of a playing-board 10 divided into squares and spaces representing "safety" and "danger zones" and "submarine bases", and a plurality of "ships" or "sea-planes" and "submarines". The game is played by two persons by manipulating the "ships" or "sea-planes" and "submarines", the desideratum being to cross the board into the enemy's "harbor" by the exercise of skill on the part of the player in moving from space to space across 20 the board, the winner of the game being the one who gets the largest amount of tonnage into the enemy's "harbor".

In the accompanying drawings:—

Figure 1 is a plan view of the board;

25 Fig. 2 is a perspective of one of the "boats" or "sea-planes";

Fig. 3 is a cross-section through the "submarine-base";

30 Fig. 4 is a view of one of the pegs which control the "submarines".

A, represents the board. This is preferably made of stiff card-board capable of being folded through the center if desired, although not necessarily so.

35 The surface of the board is divided into a plurality of squares, in the present instance fourteen each way, or making a total of one hundred ninety-six altogether. These squares are colored differently as a part of 40 the general scheme of the game. The alternate spaces 1 lengthwise and crosswise of the board are of the same color throughout, for instance white, and the remaining spaces are preferably in three different contrasting colors, for instance through the center, which is termed the "danger zone", the spaces 2 are green, with an occasional safety space 3, marked "Safety", of yellow with white centers. Two rows of spaces 45 at the opposite ends may be blue, and this is designated as the "harbor" and the colored spaces 5 between the "harbor" and the "danger zone" may be red. All of these three rows at each end are within what is 55 known as the "three-mile limit" correspond-

ing to the recognized continental three-mile limit, which is designated "safety-zone".

At the opposite ends are two "submarine bases". These comprise strips 7 preferably of wood erected at the ends and having a 60 number of diagonally-bored holes 8 corresponding in number to the rows of spaces extending directly across from the board, namely fourteen in this instance, to receive balls 9 which represent the "submarines", 65 and a corresponding number of small holes 10 receive the removal pegs 11 which are inserted in all of these holes and are adapted to hold the "submarines" back in check where they cannot be seen by the opponent. 70 These are easily released at the desired time by the player by simply lifting the peg and letting the ball or "submarine" descend to the lower end of the opening where it can be seen by the opponent, and 75 which move on the part of the player means the sinking of all ships in all of the squares in line with the "submarine" thus submerged.

The placing of these comparatively few 80 "submarines" in the "submarine base" having many times the number of holes for them, constitutes a part of the skill of the player and is one of the elements of chance of the game, as it is important that their 85 location be kept from the enemy until the player allows them to submerge or drop to the lower end of the opening, where, for the first time, they become visible to the 90 opponent.

The object of the game is to get the largest amount of tonnage across the board into the enemy's "harbor", and the game is completed when no further moves can be made, at which time it is easy to figure the 95 amount of tonnage that each player has in his opponent's "harbor" and subtract the difference, giving the credit of the game to the one having the amount of tonnage in excess of the other.

100 The numeral 12 represents the "ships." These may be termed "sea-planes" or "ships" if desired. Each bears a number representing the number of thousands of tonnage the vessel carries. The "ships" besides carrying a certain amount of tonnage are armed with "guns" and "sea-planes." In passing an enemy "ship" in the "danger zone" it must be sunk or destroyed; therefore a "gun" is fired or a "bomb" is dropped 105 110

from a "sea-plane." The sunken "ship" is then removed from the board, and the player moves on to the square beyond the one on which the enemy's "ship" was destroyed. To submerge a "submarine" one of the base pegs is lifted, which allows the "submarine" to drop to the board, whereupon it sinks all "ships" in line with it on the green squares in the "danger zone."

10 *Directions for playing the game.*

This game is played somewhat like the game of checkers, in the matter of moving and "jumping" the opponent. It is for two players. Place the pegs in the top of the base. Conceal three "submarines" anywhere in the base and place at each end of the board. Place "ships" in the "harbor" on the blue squares.

20 1. The players move in turn, diagonally across the board and always from them, except to enter or leave the "safety" which may be done from any direction.

2. Leaving or entering the "harbors" or "three-mile limit" ("safety zones"), the player is permitted to pass over or around his or his opponent's "ship" without removing it from the board.

3. Passing from the "three-mile limit" to "danger zone," the player cannot pass his own "ship," but must move one square at a time except to destroy an enemy's "ship" which may be in an adjoining square. He may sink, by removing from the board, one or more "ships" providing there is a space between the "ships" on which the "sea-plane" may alight.

4. Launching a "submarine": "U-23" sinks all "ships" of both players which may be on the squares directly across the board, in the "danger zone." This constitutes a move. The "sub" is not removed from the base until the game is finished.

5. The player who succeeds in anchoring the greater number of tons in the opponent's "harbor" wins the game. The count is taken when there are no more moves for one of the players.

6. Tonnage is counted of only those ships

in the "harbor" "over there." Each number on the "ship" represents the tons by the hundred. A player anchoring numbers 50, 25, 40, and 80, has 145,000 tons to his credit.

7. A player cannot be forced by his opponent to sink a "ship" or to leave a "safety."

"Ships" are destroyed only on the green squares. "Safeties" are marked on the board in blue, red and yellow.

"Ships" within "three-mile limit" which are not in the "harbor" do not score.

I claim:

1. A game comprising a board, a portion at least of the surface of which is divided into spaces, and movable objects representing submarines or the like, the positions of which are concealed from each opponent player, and means within the control of each player for liberating said movable objects when desired onto the board.

2. A game comprising a board, a portion at least of the surface of which is divided into spaces, movable objects representing submarines or the like, the positions of which are concealed from each opponent player, means within the control of each player for liberating said movable objects when desired onto the board, and other movable objects adapted to be moved by each player upon the board.

3. A game comprising a board which is divided into zones and bases, movable objects representing ships or the like adapted to be moved by the player upon the board, and movable objects representing submarines concealed from the opponent but controllable by each player.

4. A game comprising a board divided into spaces, certain of which constitute "safety and danger zones" and safety spaces, objects such as "ships" to be moved thereon, "submarine bases," "submarines" therein, and means for concealing said "submarines" from the enemy and for submerging them at the desired time.

In testimony whereof I affix my signature.

MARY DEUELL GEORGE.
